US00D971979S

(12) **United States Design Patent** (10) Patent No.: **US D971,979 S**
(45) Date of Patent: **** Dec. 6, 2022**

(54) **ROBOT**

(71) Applicant: **SONY CORPORATION**, Tokyo (JP)

(72) Inventor: **Noriaki Takagi**, Kanagawa (JP)

(73) Assignee: **SONY CORPORATION**, Tokyo (JP)

(**) Term: **15 Years**

(21) Appl. No.: **29/753,375**

(22) Filed: **Sep. 30, 2020**

Primary Examiner — Patricia A Palasik

(74) *Attorney, Agent, or Firm* — Michael Best and Friedrich LLP

CLAIM

The ornamental design for a robot, as shown and described.

DESCRIPTION

FIG. 1 is a perspective view of a robot showing my new design;

FIG. 2 is a front elevational view thereof;

FIG. 3 is a rear elevational view thereof;

FIG. 4 is a left side elevational view thereof, a right side elevational view being a mirror image; and, FIG. 5 is a top plan view thereof.

The broken lines illustration portions of the robot form no part of the claimed design. The dot-dash broken lines defining the boundaries of the claimed design form no part of the claimed design.

1 Claim, 5 Drawing Sheets
